CLAIM

The ornamental design for a neck tie as shown and described.

DESCRIPTION

FIG. 1 is a perspective view of a neck tie showing my new design;

FIG. 2 is a front view thereof;

FIG. 3 is a rear view thereof;

FIG. 4 is a top view thereof;

FIG. 5 is a bottom side view thereof;

FIG. 6 is a left side view thereof; and,

FIG. 7 is a right side view thereof.

The broken lines along the surfaces of the neck tie depict claimed stitching.
